OIL COOLING ARRANGEMENT FOR AIR-COOLED INTERNAL COMBUSTION ENGINES

Application filed August 22, 1930, Serial No. 477,101, and in Italy August 29, 1929.

It is known that in usual internal combustion engines a considerable part of the heat is transferred by the cylinder walls and piston heads to the lubricating oil, which tends to reach very high temperatures capable of objectionably affecting its lubricating properties. The dispersion and radiation of heat from the walls of the engine casing along which air flows, particularly during operation, tend to keep the oil temperature within admissible unobjectionable limits.

The amount of heat transferred to the lubricating oil is, however, a considerably larger one in air cooled engines since the temperature of the cylinder and piston walls is in this case substantially higher than in water-cooled engines.

Consequently, the casing surface is not always sufficient to abstract the heat from the oil and to keep the oil temperature within suitable limits, more particularly when the car is driven at low speed.

For this purpose it is advantageous to provide the engine with an efficient oil cooling device working independently of the engine speed.

In the arrangement according to this invention the same fan serving for cooling the engine cylinders is caused to act on the circulating oil and to cool this latter in a direct proportion to the number of turns of the fan, in addition to the normal cooling through dispersion of heat from the casing.

For the above purpose a coil is arranged in the casing of the centrifugal pump employed for the forced air circulation, said coil being connected to the pressure oil conduit, in such a way, however, that it may be cut out at will therefrom when so required by weather conditions.

The accompanying drawing shows diagrammatically and by way of example a constructional form of this invention.

Figure 1 is a longitudinal section showing the cooling arrangement applied to the fan of an air cooled engine.

Figure 2 is a cross section through the fan chamber.

The centrifugal fan 1 arranged at the front

end of the engine supplies the air for cooling the cylinders to the upper feeding conduit 2. On the inner surface of the casing 4 enclosing the fan 1 is arranged a coil 3 in which the oil delivered under pressure by the engine through a suitable conduit is caused to circulate. 5 is the oil inlet (Fig. 2) and 6 is the outlet through which the oil issues from the coil cooled by the fan, said coil being cut out, when the atmospheric conditions should require it, through a conduit 8 by a cock 7 operated by hand or through a suitable thermostatic arrangement.

All the air blown by the fan flows along the coil C, so that the oil is efficiently cooled proportionally to the number of turns of the engine in a similar manner as in cylinder cooling.

What I claim is:

In combination with an internal combustion engine, a fan supplying cooling air to said engine, a coil arranged in the fan outlet chamber and adapted to be put in the engine oil circulation and a by-pass for short-circuiting said coil.

In testimony that I claim the foregoing as my invention, I have signed my name.
